UNITED STATES PATENT OFFICE.

HENRY JOHNSON, OF ALTAVISTA, VIRGINIA.

APPARATUS FOR TOBACCO CURING.

Application filed April 10, 1920. Serial No. 372,920.

To all whom it may concern:

Be it known that I, HENRY JOHNSON, a subject of the King of England, residing at Altavista, in the county of Campbell and State of Virginia, have invented new and useful Improvements in Apparatus for Tobacco Curing, of which the following is a specification.

My present invention has to do with the curing of tobacco, and it contemplates the provision of a process of and apparatus for expeditiously drying and coloring tobacco in such manner that sponging and scalding of the tobacco is averted and the coloring 10 may be nicely and exactly regulated by positive variation of the temperature to which it is subjected, and then rapidly and thoroughly "ordering" the tobacco—i. e., rendering it pliable by the action of moisture to 15 perfectly fit it to be handled and stored.

To the attainment of the foregoing, the invention consists in the improvement as hereinafter described and definitely claimed.

In the accompanying drawings, hereby 25 made a part hereof:

Figure 1 is a perspective view of a barn equipped with my novel apparatus.

Figures 2 and 3 are horizontal sections showing flue arrangements.

Figure 4 is a horizontal section showing 30 one mode of distributing either hot air or steam to various points in the interior of the barn.

Figure 5 is a perspective of a unitary 35 portable furnace, embodying my invention.

Figure 6 is a longitudinal vertical section of the furnace.

Figure 7 is a transverse vertical section of the same.

Similar numerals designate corresponding 40 parts in Figures 1 and 2 to which reference will first be had.

In the carrying out of my invention I arrange the furnace 1 in the barn 2 in such 45 manner that the face or outer end of the furnace is flush with the wall of the barn, this being advantageous inasmuch as it renders it convenient for an operator to supply the furnace with fuel and to regulate the temperature in the barn from a point exterior 50 of the same. The peculiar construction of the furnace will be hereinafter explicitly set forth, and it will suffice here to state that the furnace is provided at 3, Figure 2, with 55 an outlet for smoke and heated products of

combustion. The said outlet 3 is in the form of a flue, and as shown in Figure 2 the said flue is arranged in the barn, preferably at a slight distance above the floor thereof, and is provided with a T-head 4, which in turn 60 is merged into forwardly extending pipes 5, that extend to a point adjacent to the front end of the barn where they communicate through a pipe 6, with an uptake 7, that is arranged exteriorly of the barn as shown in 65 Figures 1 and 2.

At this point I desire it understood that I do not desire to be understood as confining myself to the flue arrangement just described or to any other specific flue arrangement. 70 For instance, the flues 4^a may be arranged as shown in Figure 3, the outlet 3 being connected with pipes 5^a which in turn are merged into respective uptakes 7^a, arranged exteriorly of the barn.

By comparison of Figures 5, 6, and 7 with Figure 4 the construction and utility of my novel furnace will be understood when it is stated that the furnace comprises a fire box 8, an ash pit 9, doors 10 complementary to the fire box and arranged exteriorly of the barn, Figure 1, doors 11 complementary to the ash pit and also arranged exteriorly of the barn, a grate 12 which may be adapted for the burning of either wood 80 or coal as conditions make necessary, an inner wall 13, and an outer wall 14, separated by an intervening air space 14^a from the inner wall. It being remembered that the major portion of the furnace is arranged 90 within the barn 2, it will be appreciated that the employment of the two walls 13 and 14 separated by the air space 14^a serve the highly important purpose of practically averting fire in the event of any of the tobacco in the barn falling upon the furnace.

It will also be noticed in this connection that the said separated walls and intervening air space practically do away with the liability 95 of the furnace setting fire to the front wall 100 of the barn in which the front portion of the furnace is housed as shown in Figure 1. In addition to the intervening air space 14^a serving the important purposes ascribed to the same the said air space 14^a is adapted 105 to conduct air from induction orifices 15 in the front wall of the furnace at points adjacent to the sides thereof to an outlet pipe 16 leading from the rear or inner end of the furnace, so that the air en route is heated. 110

It will also be appreciated that this circulation of air through the space 14^a is calculated to improve or increase the insulating quality of the air which is depended upon to prevent the firing of any tobacco that may fall upon the furnace or the setting afire of the front wall of the barn. As shown in Figure 4, I prefer to connect distributing pipes 17 to the pipes 16 so that hot air may be conveyed to and discharged from the open ends of the pipes at various points in the interior of the barn as conditions require. Dampers or valves may be inserted at suitable points, such dampers being marked 30, 31 and 32.

As best shown in Figures 6 and 7 I provide in the air space 14^a of the furnace a foraminous pipe 21. The said pipe 21 is preferably, though not necessarily, disposed in the longitudinal center of the furnace and extends practically throughout the length of the air space 14^a. At one end the pipe 21 is connected through a pipe 22 with a water tank 23, the latter, being disposed exteriorly of the barn as illustrated.

In practicing my process and operating to advantage my novel apparatus, tobacco is placed in the barn in the ordinary or any other desired manner, and a fire is started in the fire box 8 and is maintained for a sufficient period to dry out the tobacco and to incidentally bring the tobacco to a bright color. This step ordinarily requires about twenty four hours, and during the same the operator is enabled by manipulation of the door 11 to vary the temperature and in that way nicely regulate the coloring of the tobacco.

As is well known to those versed in the care of tobacco it is necessary after drying and coloring to "order" the tobacco—i. e., render it pliable and eliminate its fragile or brittle characteristic. Therefore after the drying and coloring step alluded to is completed, I let water into the pipe 21. The said water will be discharged from the said pipe 21 upon the crown sheet or wall of the fire box 8 and will be immediately reduced to steam, and this steam will be discharged through the outlet 16 and by the distributing pipes in communication with said outlet 16 will be conducted to various points in the interior of the barn so as to effect the ordering of the tobacco expeditiously and thoroughly.

While I do not desire to be understood as confining myself to a unitary, portable, furnace such as illustrated, I prefer to employ such furnace because of the facility

with which the same may be handled and 60 installed in a barn.

Having described my invention, what I claim and desire to secure by Letters-Patent, is:—

1. Apparatus for treating tobacco comprising a treater chamber, a furnace, the furnace including a firebox and an outer casing extending around the firebox from and to points below the same and defining with the firebox a hollow space for heating air, 70 a pipe in said hollow space for discharging water upon the firebox and means connected with the hollow space for distributing the steam thereby generated, throughout the chamber.

2. Apparatus for treating tobacco comprising a treater chamber, a furnace, the furnace including a firebox and an outer casing extending around the firebox from and to points below the same and defining 80 with the firebox a hollow space for heating air, an air inlet to the hollow space, a pipe in said hollow space for discharging water upon the firebox and means connected with the hollow space for distributing the steam thereby generated, throughout the 85 chamber.

3. Apparatus according to claim 1 including a heat-transmitting conduit connected with the fire box and extending centrally of 90 the chamber to near the rear wall thereof, branching to both sides toward the side walls, then extending forwardly to near the front wall of the chamber, then again toward the center and uniting in a single conduit passing through the front wall of the chamber.

4. Apparatus for treating tobacco comprising a barn, a furnace arranged in the barn and having one of its ends disposed in a wall of the barn and exposed to the exterior 100 thereof; the said furnace having a fire box and an ash pit separated by a grate and also having means complementary to the ash pit for the regulation of heat and inner and outer walls and an intervening air space 105 about the fire box, outlets complementary to the fire box and the air space, respectively, means to supply air to the air space, an uptake arranged exteriorly of the barn, a flue arranged in the barn and interposed 110 between and connecting the furnace outlet and the uptake, means for generating steam within the air space, and distributing means for hot air and steam connected with the outlet of the air space and disposed in the 115 barn.

In testimony whereof I affix my signature.
HENRY JOHNSON.
